UNITED STATES PATENT OFFICE.

JOSEPH C. HITCHNER, OF PHILADELPHIA, PENNSYLVANIA, ASSIGNOR TO H. AND R. GARTER CO., INCORPORATED, OF PHILADELPHIA, PENNSYLVANIA.

CLASP.

1,177,329.

Specification of Letters Patent.

Patented Mar. 28, 1916.

Application filed August 29, 1914. Serial No. 859,148.

To all whom it may concern:

Be it known that I, JOSEPH C. HITCHNER, a citizen of the United States, residing at Philadelphia, in the county of Philadelphia and State of Pennsylvania, have invented certain new and useful Improvements in Clasps, of which the following is a specification.

My invention relates to improvements in 10 clasps, and more particularly to a clasp designed for use on garters or other similar garment supporters, and which is especially adapted for use in connection with hose supporters to firmly grip the hose without danger of tearing or drawing the threads thereof, and which will lie flat and smooth 15 against the leg, rendering the clasp comfortable for the user.

A further object is to provide a clasp of 20 the character stated which can be easily and quickly operated to grasp the hose or to release the hose, a simple movement of the thumb or finger being all that is necessary to release the clasp.

25 A further object is to provide a clasp of the character stated which cannot accidentally release, and which will be comparatively simple in construction, cheap to manufacture and ornamental in appearance.

30 With these and other objects in view, the invention consists in certain novel features of construction and combinations and arrangements of parts as will be more fully hereinafter described and pointed out in 35 the claims.

In the accompanying drawings: Figure 1 is a perspective view illustrating my improved clasp in closed position. Fig. 2 is a rear view of the clasp on an enlarged scale. 40 Fig. 3 is a view in vertical longitudinal section through the center of the clasp showing the same in closed position. Fig. 4 is a view similar to Fig. 3 showing the clasp in open or released position with the bail in 45 the hook but before any tension is applied to the bail by the movement of the pivot plate, and Fig. 5 is a view in elevation of the locking bail.

1 represents a frame which is composed of 50 a single piece of wire bent between its ends forming an oblong loop 2. The wires on the upper side of the loop 2 are spaced apart and bent at right angles to the upper member of the loop as shown at 3, and extend 55 upwardly parallel to each other as shown at

4. The wires then bend outwardly at a sharp right angle forming journals 5, and then bend inwardly at an acute angle extending toward each other in a general inclined direction as shown at 6, and the extreme ends of the wires are then bent forming a loop 7 preferably having rounded ends 8 as shown. The frame thus formed is bent outwardly at its intermediate portion as shown clearly in Figs. 3 and 4, so that the journals 5 are located in a vertical plane 60 in advance of the vertical plane of the loops 7 and 2 for a purpose which will hereinafter appear.

9 represents a plate which is secured to the front of the loop 2 by means of tongues 10 on the ends of the plate which are bent around the end portions of the loop and at the upper edge of this plate 9, I provide a relatively wide hook 11 adapted to receive 70 the intermediate portion 12 of a bail 13. This bail 13 is pivotally connected to and carried by a pivot plate 14, and said pivot plate is provided at its lower edge with 75 bearings 15 formed by bending integral tongues on the edge of the pivot plate into cylindrical form and around the journals 5, so that the plate 14 is free to pivot on the journals. At the upper edge of the plate 14, I provide a tongue 16 which is integral 80 with the plate and located at the center of its upper edge, and at both sides of the tongue 16, I provide on the plate integral sleeves 17 which receive the inwardly bent ends 18 of bail 13.

I would call particular attention to the shape of the bail 13 and the shape of the pivot plate 14. The bail 13, at its intermediate portion 12, is bowed upwardly to provide rounded portions 19 at the sides of the bail, which not only accommodate the goods without pinching the same, but also give a certain amount of elasticity to the bail. Furthermore, it will be noted by reference particularly to Figs. 3 and 4, that the side members of the bail are bowed outwardly 95 from end to end, which gives to the bail the necessary amount of elasticity to permit it to expand and contract in accordance with the position of the pivot plate. By reference also to Figs. 3 and 4, it will be seen that the pivot plate at its upper edge, where the sleeves 17 are located, is bent inwardly, so that when the pivot plate is in its closed or locking position, the sleeves 17 will be in a 100 110

- plane inside of the plane of journals 5. In other words, the ends 18 of the bail 13 will be forced past the pivot point of plate 14, and a positive lock will be had.
- 5 In operation, the hook 11 is placed under the hose, and the bail 13 is positioned over the outside of the hose, gathering a portion of the hose under the hook 11. Fig. 4 illustrates this first position of the clasp, and 10 when in this position, an upward and inward pressure against the tongue 16 will force the pivot plate to the position shown in Fig. 3, so that the ends 18 of the bail are forced upwardly and inwardly past the pivot point or 15 center of the pivot plate 14. In assuming this position, the bail is expanded longitudinally, so that it obtains a tight gripping action, and also maintains the pivot points in the position shown in Fig. 3, requiring some 20 force to overcome this spring tension before the bail can be released. The tongue 16 is, however, in a convenient position to receive the thumb or finger of the operator and permit the same to be forced outwardly, and as 25 soon as the ends 18 are moved outwardly beyond the vertical plane of the journals 5, the elasticity of the bail will throw the bail to open or released position. It is therefore 30 simply necessary for the operator to force the tongue 16 outwardly and the elasticity of the bail will accomplish the further opening or releasing movement. In order to give this necessary elasticity, the wire will, of course, be made of spring metal, and 35 while my invention is not limited to any particular supporting means, I have shown a webbing 20 which is run through the upper loop 7 and against which the end of the tongue 16 is adapted to bear, so that it will 40 be held out of engagement with the leg of the user.
- Various slight changes might be made in the general form and arrangement of parts described without departing from my invention, and hence I do not limit myself to the 45 precise details set forth, but consider myself at liberty to make such changes and alterations as fairly fall within the spirit and scope of the appended claims.
- 50 Having thus described my invention, what I claim as new and desire to secure by Letters Patent is:
1. A clasp comprising a frame having a hook thereon at one end, a pivot plate pivotally connected to an intermediate portion of the frame, and a spring bail pivotally connected to the pivot plate at a point above the pivotal connection of the latter and having its side portions bowed, said bail adapted to be positioned in engagement with the hook and of a normal length shorter than the distance between the hook and the point of attachment of said bail with the pivot plate 55 when the latter is in its locking position, substantially as described.
2. A clasp comprising a frame having a hook thereon at one end, a pivot plate pivotally connected to an intermediate portion of the frame, and a spring bail pivotally connected to the pivot plate at a point above the pivotal connection of the latter and having its side portions bowed, said bail adapted to be positioned in engagement with the hook and of a normal length shorter than the distance between the hook and the point of attachment of said bail with the pivot plate 60 when the latter is in its locking position, said frame bent intermediate its ends, whereby the pivot point of the plate is located in a different vertical plane from the pivot point of the bail when the pivot plate is in its locking position, substantially as described. 75
3. A clasp comprising a wire frame having journals intermediate its ends projected outwardly in a plane beyond the plane of the ends of the frame, a pivot plate pivotally connected to said journals, a hook on one end of the frame, and an elastic bail pivotally connected to the pivot plate at a point above the pivot point of the latter, at a point above the pivot point of the latter, and adapted to engage the said hook, whereby the pivotal connection of the bail and the pivot plate is located inwardly beyond the 80 said journals when the pivot plate is in locking position, substantially as described. 85
4. A clasp comprising a frame having a hook thereon at one end, a pivot plate pivotally connected to an intermediate portion of the frame, and a spring bail pivotally connected to the pivot plate at a point above the pivotal connection of the latter and having its side portions bowed, said bail adapted to be positioned in engagement with the hook and of a normal length shorter than the distance between the hook and the point of attachment of said bail with the pivot plate 90 when the latter is in its locking position, and an operating tongue on the edge of the 95 said pivot plate, substantially as described. 100
- 45 A clasp comprising a frame having a hook thereon at one end, a pivot plate pivotally connected to an intermediate portion of the frame, and a spring bail pivotally connected to the pivot plate at a point above the pivotal connection of the latter and having its side portions bowed, said bail adapted to be positioned in engagement with the hook and of a normal length shorter than the distance between the hook and the point of attachment of said bail with the pivot plate 105 when the latter is in its locking position, and an operating tongue on the edge of the 110 said pivot plate, substantially as described. 115
5. A clasp, comprising a frame having a hook thereon at one end, a pivot plate pivotally connected to an intermediate portion of the frame, and a spring bail pivotally connected to the pivot plate at a point above the pivotal connection of the latter and having its side portions bowed, said bail adapted to be positioned in engagement with the hook and of a normal length shorter than the distance between the hook and the point of attachment of said bail with the pivot plate 120 when the latter is in its locking position, said frame bent intermediate its ends, whereby the pivot point of the plate is located in a different vertical plane from the pivot point of the bail when the pivot plate is in its locking position, and an operating tongue on the edge of said pivot plate, substantially as described. 125
- 60
- 65
- 130

6. A clasp, comprising a wire frame having journals intermediate its ends projected outwardly beyond the plane of the ends of the frame, a pivot plate pivotally connected 5 to said journals, a hook on one end of the frame, and an elastic bail pivotally connected to the pivot plate at a point above the pivot point of the latter and having its side portions bowed, and adapted to engage the said 10 hook, whereby the pivotal connection of the bail and the pivot plate is located inwardly beyond the said journals when the pivot plate is in locking position, and an operating tongue on the edge of said pivot plate, substantially as described.

7. A clasp comprising a wire frame having loops at both ends, and having journals

intermediate its ends located in a plane beyond the plane of the loops, a hook secured to one of said loops, a pivoted plate pivotally connected to the journals, and a spring bail connected to the pivot plate above the pivotal connection of the latter and adapted to engage under the hook, said bail composed of a single piece of spring wire having its 25 side portions bowed outwardly, substantially as described.

In testimony whereof I have signed my name to this specification in the presence of two subscribing witnesses.

JOSEPH C. HITCHNER.
